United States Patent

Des. 240,254

Patented June 8, 1976

240,254

PENDANT OR SIMILAR ARTICLE

Margareta C. Roberts, Providence, R.I., assignor to Reed & Barton Corporation, Taunton, Mass.

Filed May 28, 1974, Ser. No. 473,763

Term of patent 3½ years

Int. Cl. D11—01

U.S. Cl. D45—16 A

FIG. 1

FIG. 2

FIG. 3

FIG. 4

FIG. 5

FIG. 1 is a front elevational view of a pendant or similar article showing my new design;

FIG. 2 is a rear elevational view thereof;

FIG. 3 is a right side elevational view thereof;

FIG. 4 is a top plan view thereof; and

FIG. 5 is a bottom plan view thereof.

I claim:

The ornamental design for a pendant or similar article, substantially as shown.
